UNITED STATES PATENT OFFICE.

NATHANIEL TWOMBLY, OF EASTONVILLE, COLORADO.

DOOR-LATCH.

1,213,040.

Specification of Letters Patent. Patented Jan. 16, 1917.

Application filed May 24, 1915. Serial No. 30,136.

To all whom it may concern:

Be it known that I, NATHANIEL TWOMBLY, a citizen of the United States, residing at Eastonville, in the county of El Paso and 5 State of Colorado, have invented new and useful Improvements in Door-Latches, of which the following is a specification.

The present invention relates to improvements in means for latching doors, either in 10 an open or closed position, and the primary object of the invention is to construct a simple, cheap and thoroughly effective latch which will hold a door either open or closed until the same has been manually operated, 15 so that danger of the weakening or breaking of the hinges or other parts of the door, incident to the said door being swung to and fro by the wind will be entirely overcome.

20 A still further object of the invention is to construct a simple form of latch which will automatically engage with a latch bar upon a swinging door, when the same contacts with the latch, and further whereby the door 25 may be operated from either the interior or exterior of a building.

With the above and other objects in view, the improvement resides in the construction, 30 combination and arrangement of parts set forth in the following specification and falling within the scope of the appended claim.

In the drawing, Figure 1 is an elevation of a door provided with my improved latch, Fig. 2 is a similar view approximately on 35 the line 2—2 of Fig. 1, the dotted lines illustrating the door in its open position, Fig. 3 is an elevation, partly in section, employed for holding the door in a closed position, Fig. 4 is a similar view of the latch for 40 holding the door in an open position, Fig. 5 is a perspective view of the latch bar which is secured to the door, and Fig. 6 is a similar view of the contact or bumper plate which prevents the latch bar from contacting 45 with the frame work for the door.

Referring now to the drawings in detail, the numeral 1 designates an ordinary barn door which is hingedly secured to one of the casing strips of the jamb of the door, as indicated by the numeral 2. The second vertical casing strip indicated by the numeral 3 is provided with an opening 4 through which passes the hooked end 5 of a latch 6. The latch includes a body 7 which has its end, 50 opposite that provided with the hook 5 formed with what I will term a tail 7', and

the body is pivotally connected, as at 8, between a supporting plate 9 and a bracket member 10, the bracket being also secured to the plate 9, as at 11. The tail of the 60 latch to the rear of the pivot 9 is provided with an opening 12 through which is passed an adjustable member 13 preferably in the nature of a bolt, nuts 14 and 15 being 65 threadedly connected to the opposite ends of said bolt 13, and the nut 14 rests upon the upper face of the tail 7' of the latch. The second end passes through an elongated opening in the bracket 15', while surrounding the said bolt and exerting a tension between the tail of the latch and the bracket 70 15' is a helical spring 16. The tension of the spring may be regulated by adjusting the nut 14, as will be readily understood and as the hooked end 5 of the bolt is formed 75 with a goose-neck extension 17, the same may be swung upon its pivot 8, either from the extension 17 or from the tail 7'. The bolt 13, it will be noted, serves manually as a guide means for the spring 16, while the 80 nuts 14 and 15 serve as means for adjusting the pressure of the spring between the bracket 15' and the latch 6 adjacent the tail portion 7' of the said latch so that its hook 5 will be brought into proper contacting position as well as for limiting the upward 85 swinging of the tail of the latch.

The numeral 18 designates a latch plate or strip which is secured to the outer face of the door 1 and which is adapted to be 90 engaged by the hooked end 5 of the latch. In order to prevent the strip 18 from contacting with the framework of the doorway, I provide an abutment plate 19, the same being preferably constructed of metal and 95 being arranged so as to be contacted by the plate 18 when the door is swung to its closed position. In order to retain the door latched when in an open position, I provide a second latch member, indicated by 100 the numeral 20, the same adjacent its hooked end, indicated by the numeral 21, being of a goose-neck formation, as indicated by the numeral 22, so that the same may be swung upon its pivot 23. The pivot 23 passes 105 through a suitable plate 24, the plate, in the present instance, being provided with an angular extension or bracket 25, and the lower end of the said bracket 25 is provided with an offset portion or foot 26. The foot 110 26 of the bracket is provided with an opening through which is passed an adjustable

member, in the nature of the bolt 27, and the said bolt also passes through an elongated opening in the tail 28 of the latch 20. Nuts 29—29 are connected to the opposite threaded ends of the bolt 27, which project both beyond the tail of the latch and below the foot of the bracket, and surrounding the said bolt 27 and exerting a tension between the bracket and the foot of the bracket is a helical spring 30.

From the above description, taken in connection with the accompanying drawing, the simplicity of the device, as well as the advantages thereof will, it is thought, be perfectly apparent to those skilled in the art to which such invention appertains without further detailed description.

Having thus described the invention, what I claim is:

20 In a device for the purpose set forth, a plate having a bracket secured thereon, a latch including a body portion pivotally

secured between the bracket and plate, said latch having one of its ends formed with a hook and an upwardly and downwardly curved finger engaging portion extending from the hook, the second end of the hook comprising a thumb engaging extension and the said end at a distance from the rounded portion thereof being provided with an elongated opening, a second bracket upon the plate also provided with a registering elongated opening, a convolute spring upon the last mentioned bracket and contacting with the latch, a member loosely passing through the openings and through the convolutions of the spring, and adjustable elements upon the opposite ends of the said member.

In testimony whereof I affix my signature in presence of two witnesses.

NATHANIEL TWOMBLY.
